UNITED STATES PATENT OFFICE

137,707

DESIGN FOR A BABY CARRIAGE

Fred H. Fink, New York, N. Y.

Application May 21, 1943, Serial No. 110,246

Term of patent 7 years

(Cl. D14—14)

To all whom it may concern:

Be it known that I, Fred H. Fink, a citizen of the United States, residing at New York, in the county of New York and State of New York, have invented a new, original, and ornamental Design for Baby Carriages, of which the following is a specification, reference being had to the accompanying drawing, forming part thereof.

The figure is a side perspective view of a baby carriage, showing my new design.

The wicker portion illustrated at the front

and rear ends of the carriage body extends from the top as shown, to the underneath section thereof, adjoining the front and rear axle members respectively. The opposite side of the baby carriage is substantially similar to that shown in the drawing.

I claim:

The ornamental design for a baby carriage, as shown and described.

FRED H. FINK.
